UNITED STATES PATENT OFFICE

97,548

DESIGN FOR A TABLE OR SIMILAR ARTICLE

Alta Beane Davis, Los Angeles, Calif.

Application July 25, 1934, Serial No. 52,685

Term of patent 3½ years

To all whom it may concern:

Be it known that I, Alta Beane Davis, a citizen of the United States, residing at Los Angeles, in the county of Los Angeles and State of California, have invented a new, original, and ornamental Design for a Table or Similar Article, of which the following is a specification, reference being had to the accompanying drawing, forming a part thereof.

The figure is a perspective view of the article showing my new design.

I claim:

The ornamental design for a table or similar article substantially as shown.

ALTA BEANE DAVIS.
